James J. Johnston

UNITED STATES PATENT OFFICE.

JAMES J. JOHNSTON, OF ALLEGHENY CITY, PENNSYLVANIA.

IMPROVEMENT IN WOODEN SOLES FOR BOOTS AND SHOES.

Specification forming part of Letters Patent No. 36,715, dated October 21, 1862.

To all whom it may concern:

Be it known that I, JAMES J. JOHNSTON, of the city and county of Allegheny, in the State of Pennsylvania, have invented certain new and useful Improvements in Wooden Soles for Boots and Shoes; and I do hereby declare that the following a full and exact description thereof, reference being had to the accompanying drawings, and to the letters of reference marked thereon.

The nature of my invention consists in the use of a detached, compressed, and elastic spring when used in connection with the inner and outer soles of boots and shoes, said soles being made of wood and in two or more parts, the whole being arranged, constructed, and operated in the manner hereinafter described.

To enable others skilled in the art to make and use my invention, I will proceed to describe its construction and operation.

In the accompanying drawings, Figure 1 is a face view of the under side of the outer sole. Fig. 2 is a face view of the back part of the outer sole. Fig. 3 is a face view of the front part of the outer sole. Fig. 4 is a cut or sectional view (lengthwise) of the inner sole. Fig. 5 is a cut or sectional view (lengthwise) of the outer sole. Fig. 6 is a cut or sectional view (lengthwise) of the inner and outer sole, and represents my arrangement of the compressed, detached, and elastic spring, and the hinge which holds the front and back part of the outer sole together. Fig. 7 is a top view of the hinge. Fig. 8 is a cut or sectional view of the hinge. Fig. 9 is a cut or sectional view of the spring. Fig. 10 is a top view of the spring.

The soles should be made of good, clear, hard wood, with its grain running in an oblique line lengthwise of the sole, as indicated by the red line marked o. The inner (insole) sole is made thinner and smaller than the outer sole.

In the accompanying drawings, a is the heel. b is the shank of the outer sole. c is the front part of the outer sole. d is the front part of the inner sole, and e is the back part.

f is a recess made in the under side of the inner sole at the joint for the purpose of receiving the hinge.

g is a recess made in the upper side of the

outer sole for the purpose of receiving the spring which covers and protects the joint h—that is to say, it makes the outer sole air and water proof at the joint.

i is the elastic spring, and is made larger than the recess g, and is compressed into the recess, and there held by the hinge j, which is placed over it and secured to the outer sole by means of screws. The hinge j is made of leather, (but may be made of any other suitable material,) and is furnished with a rib, x, which is placed between the back and front part of the inner sole at the point where they join each other. It will be observed that the detached and elastic spring is made larger than the recess into which it is compressed, and that by thus compressing it into the recess g, and it not being attached to the sole, the joint h will be kept perfectly air and water proof, and that the compressed and elastic spring (which is made of india-rubber) will cause the sole of the boot or shoe to follow the movements of the foot, imparting to the wooden sole the spring and natural feeling and action of a sole made from leather.

In putting the upper to the soles the inner sole is placed on the last, and the upper-leather is secured to it by pegs or other means common in the process of securing wooden soles on boots or shoes. The outer sole being secured together by means of the hinge i, with the detached elastic spring compressed into the recess g, it is then secured to inner sole by means of screws or any other suitable means.

It will be observed that by the use of a detached spring it is not liable to be rendered inoperative by becoming torn or broken into two or more parts by the constant straining and stretching of the spring, caused by movements of the foot; and it will also be observed that by the use of the compressed and detached spring the sole of the shoe or boot will always be pressed against the sole of the foot of the wearer, for the compressed and detached spring will cause the front part of the sole of the boot or shoe to spring upward toward the sole of the foot.

I am aware that an elastic hinge permanently attached to the sole has been used in connection with wooden soles for boots and shoes. Such device is seen in the patent granted to Alexander Hanvey, May 1, 1860; and I

am also aware that hinges have been made of leather, steel, and other material, and used in connection with wooden soles for boots and shoes. I therefore do not claim the hinge. Neither do I claim, broadly, the use of the elastic spring; but,

Having thus described the nature, construction, and operation of my improvement, what I claim as of my invention, and desire to secure by Letters Patent of the United States, is—

The use of the detached elastic spring *i*, when used in connection with the hinge *j*, recess *g*, outer sole, *b* *c*, and inner sole, *d* *e*, arranged, constructed, and operated substantially as herein described, and for the purpose set forth.

JAMES J. JOHNSTON.
